US00D345107S

United States Patent

[19]

Williams

[11] Patent Number: Des. 345,107

[45] Date of Patent: ** Mar. 15, 1994

[54] **PROGRAMMABLE ADDITIVE
CONTROLLER**

[75] Inventor: **Gary E. Williams**, Atlanta, Ga.

[73] Assignee: **Titan Industries, Inc.**, Atlanta, Ga.

[**] Term: **14 Years**

[21] Appl. No.: **890,791**

[22] Filed: **Jun. 1, 1992**

[52] U.S. Cl. **D10/46; D10/102**

[58] Field of Search 222/1-3,
222/14, 16, 23-30; D10/46, 96-101, 123, 125

[57] **CLAIM**

The design for the programmable additive controller, as shown.

DESCRIPTION

FIG. 1 is a front elevational view of a programmable additive controller showing my new design;

FIG. 2 is a top view of the device shown in FIG. 1;

FIG. 3 is a bottom view of the device shown in FIG. 1;

FIG. 4 is a left side view of the device shown in FIG. 1;

FIG. 5 is a right side view of the device shown in FIG. 1; and,

FIG. 6 is a rear view of the device shown in FIG. 1.

FIG. I

FIG. 2

FIG. 3

FIG. 4

FIG. 5

FIG. 6
